(57) **CLAIM**

I claim the ornamental design for a lacrosse training mat, as shown and described.

DESCRIPTION

FIG. 1 is a perspective view of the lacrosse training mat of the present invention;

FIG. 2 is a top view of the lacrosse training mat of the present invention;

FIG. 3 is a front elevational view of the lacrosse training mat of the present invention;

FIG. 4 is a right side view of the lacrosse training mat of the present invention;

FIG. 5 is a bottom view of the lacrosse training mat of the present invention;

FIG. 6 is a left side view of the lacrosse training mat of the present invention; and,

FIG. 7 is a rear elevational view of the lacrosse training mat of the present invention.

The broken lines in the figure views depict environment that form no part of the claimed design.
